UNITED STATES PATENT OFFICE.

JOSEPH J. KULAGE, OF ST. LOUIS, MISSOURI.

BRICK-MACHINE.

SPECIFICATION forming part of Letters Patent No. 309,549, dated December 23, 1884.

Application filed May 19, 1884. (No model.)

To all whom it may concern:

Be it known that I, JOSEPH J. KULAGE, of St. Louis, Missouri, have made a new and useful Improvement in Brick-Machines, of which 5 the following is a full, clear, and exact description, reference being had to the annexed drawings, making part of this specification, in which—

Figure 1 is a side elevation of the improved machine; Fig. 2, a vertical longitudinal section; Fig. 3, a plan; Fig. 4, an end elevation, partly broken away, looking toward the delivery end of the machine; Fig. 5, a horizontal section on the line 5 5 of Fig. 4; Fig. 6, a section 15 on the line 6 6 of Fig. 4; Fig. 7, a vertical section on the line 7 7 of Fig. 4; Fig. 8, a plan of the cross-head, and Fig. 9 an elevation of the catch used in preventing the back action of the toggle and plunger.

20 The same letters of reference denote the same parts.

The present invention is an improvement in dry-clay machines.

The improvement relates to the mechanism 25 for imparting the movement to the plungers, to the construction of the toggle, to the operation of the plungers, and to various minor points hereinafter described, and designated in the claims.

30 A A' represent two gear-wheels, attached, respectively, to the shafts B B'. The shaft B' is the driving-shaft of the machine. It is provided with the pinions A² A³, which engage, respectively, with the wheels A A'. The 35 shafts B B' turn in suitable bearings, b b, in the frame C. The wheels A A' are united by means of the wrist-pin D, and in effect form a double crank for operating the pitman E. The pitman at its forward end is connected 40 with the cross-head F, which is adapted to work in the slides G G.

H H' represent links which at one end are pivoted to the cross-head at h h, and at the other end are jointed to the toggles I I'. The 45 toggles turn on the bearings i i', respectively, in the forward end of the frame C, as shown more distinctly in Figs. 1, 2. By means of the links i i' the toggles are jointed to the plungers J J', respectively. The plungers are 50 adapted to work upward and downward in the guides K K, and to operate in connection

with the mold-frame L. The mold-frame has cells or molds l l l l, in which the bricks are formed, and is arranged between the plungers. The lower plunger, J', has sub-plungers j j j j', which are adapted to work upward through the molds l l l l, and the upper plunger, J, is adapted to work downward, its sub-plungers j j j j passing downward into the molds.

60 The operation of the machine is as follows: As the wheels A A' in their rotation operate to thrust the pitman to its forward limit, and thereby withdraw the plungers, respectively, downward and upward to open the molds, a 65 charger, M, is caused to move forward beneath the hopper N, and thereby fill the molds with clay. The charger is actuated as follows: Two rods, m m, lead from the charger and respectively on each side of the pitman, and at their rear ends are jointed to the bell-crank levers m' m', respectively. These levers m' m' are journaled, respectively, at m² m² in the frame C, and the arm m³ of the toggle is adapted to be moved by means of the guide a², which is attached to the wheel A, and whose peculiar shape is shown in Figs. 1, 2—that is, each wheel A and A' has a guide, a², which operates the bell-crank lever belonging to it. The continued rotation of the wheels A A' causes 70 the bell-crank levers to be turned on their journals, and the charger in consequence to be moved forward and backward, as described, and so as to deposit the clay in the molds. As the charger moves forward its front end, 75 m⁴, pushes the bricks previously formed off onto a suitable receiving-table. The upper plunger is passed by the charger in its forward movement by reason of the end m⁴ being made sufficiently low. The sides m⁶ m⁶ of the charger are made higher. During the charging of 80 the molds the plungers are stationary. This is accomplished by elongating the strap e of the pitman E, so that while the wheels A A' are acting upon the bell-crank levers they do 85 not act to move the pitman. After charging the molds the wheels A A' act again upon the pitman, and cause the pitman to be drawn backward, and the plungers, through the links H H' and toggles I I', to be moved toward each 90 other, the sub-plungers of the lower plunger entering the molds, or rather passing upward 95 other, the sub-plungers of the lower plunger entering the molds, or rather passing upward 100 other, the sub-plungers of the lower plunger entering the molds, or rather passing upward

in the molds, (as the lower sub-plungers never entirely drop out of the molds,) and the upper sub-plungers passing downward into the molds and suitably thereinto, to cause the clay 5 to be properly pressed to form the bricks. The wheels A A' continuing to act on the plungers, the upper plunger is withdrawn upward above the molds, and in its upward movement the upper plunger lifts the lower plunger with 10 it, and as follows: The lower plunger is provided with the snap-hooks N N. These hooks, as the bricks are compressed, engage with the hooks or shoulders O O, upon the upper plunger, and the two plungers are thereby locked 15 together, so that the rising of the upper plunger causes the lower plunger to be lifted out of its bearings $i^3 i^2$ in the link i^1 , Fig. 7. This last-described upward movement of the lower plunger causes its sub-plungers to be projected sufficiently upward through the mold to eject the 20 bricks therefrom. The bricks are now upheld upon the lower sub-plungers and are ready to be discharged from the machine. The charger now comes forward, as described, and pushes 25 the bricks from off the sub-plungers and out of the field of the plungers. As the charger reaches its forward limit its beveled sides $m^3 m^2$, Fig. 5, encounter and cause the snap-hooks N N to be disengaged from the hooks O O. The 30 lower plunger then drops, but, and just before encountering its bearings $i^3 i^2$, its fall is arrested by the chains P P, which at one end are attached to the machine-frame and at the other end to the lower plunger. At their upper ends or at other suitable point the chains 35 are adapted to cushion the fall of the plunger, as by means of the rubber washers $p^3 p^2$, interposed between the nuts p' and the chains—that is, the chain at its upper end is provided 40 with a bolt, p^1 , which passes through the bearing p^3 and washer p^2 , and above the washer is provided with the nut p' . By suitably adjusting the nut upon the bolt the chain can be 45 adjusted to allow the plunger to drop as desired. The weight of the toggles is liable to

be overcome by that of the plungers, and, in consequence, what may be styled a "back-action" of the cross-head, &c., may occur. To insure the holding of these parts in their places until it is desired to have them move, 50 I employ the spring hook or bar Q, Figs. 1, 2, which operates in connection with the lug q on the lower toggle. The bar Q operates to sustain the free end of the toggle until the pitman, in its rearward movement, encounters 55 the bevel q' of the bar. The bar is then dislodged from beneath the toggle, allowing the toggle to move.

I claim—

1. The combination, substantially as described, of the pinions A² A³, the double wheel A A', the frame C, the pin D, the pitman E, and the cross-head F, substantially as and for the purpose described. 60

2. The combination, substantially as described, of the frame C, the double wheel A A', the pin D, the pitman E, the cross-head F, the slides G G, the links H H', the toggles I I', the plungers J J', and the guides K K. 65

3. The combination, substantially as described, of the pitman E, the cross-head F, the slides G G, the links H H', the toggles I I', the guides K K, the links $i^2 i^2$, and the plungers J J'. 70

4. The combination, substantially as described, of the frame C, the double wheel A A', the pitman E, the cross-head F, the links H H', the toggles I I', the plungers J J', the shoulders O O, the hooks N N, the charger M, the rods $m^1 m^2$, the levers $m^3 m^4$, and the guides 80 $a^2 a^2$. 75

5. The combination, substantially as described, of the wheels A A', the pitman E, having the elongated strap e, and the pin D, for the purpose described.

JOS. J. KULAGE.
